Primary Examiner — Philip S Hyder(74) *Attorney, Agent, or Firm* — Steve LeBlanc, LLC(57) **CLAIM**

The ornamental design for a utility tool attachment, as shown and described.

DESCRIPTION

FIG. 1 is a front perspective view of the utility tool attachment;

FIG. 2 is a top view of the utility tool attachment;

FIG. 3 is a bottom view of the utility tool attachment;

FIG. 4 is a left side view of the utility tool attachment;

FIG. 5 is a right side view of the utility tool attachment;

FIG. 6 is a front view of the utility tool attachment; and,

FIG. 7 is a rear view of the utility tool attachment.

The dotted lines shown in FIGS. 1-7 are environmental only and form no part of the claimed design.

1 Claim, 4 Drawing Sheets(56)
